United States Patent

Des. 238,673

Patented Feb. 3, 1976

238,673

TOILET SEAT COVER

Henry M. Stairs, Jr., Somerville, N.J., assignor to American Standard Inc., New York, N.Y.

Filed Feb. 24, 1975, Ser. No. 552,575

Term of patent 14 years

Int. Cl. D23—02

U.S. Cl. D23—71

FIG. 1

FIG. 2

FIG. 3

FIG. 4

FIG. 1 is a top plan view of the toilet seat cover embodying my new design;

FIG. 2 is a cross section taken along line 2—2 of FIG. 1;

FIG. 3 is an end view thereof;

FIG. 4 is a bottom plan view thereof.

I claim:

The ornamental design for a toilet seat cover, substantially as shown.
